UNITED STATES PATENT OFFICE.

LOUIS R. ALBERGER, OF NEW YORK, N. Y., ASSIGNOR TO WILLIAM A. PERRY
AND CHARLES C. WORTHINGTON, BOTH OF SAME PLACE.

SURFACE CONDENSER.

SPECIFICATION forming part of Letters Patent No. 447,285, dated March 3, 1891.

Application filed September 9, 1890. Serial No. 364,491. (No model.)

To all whom it may concern:

Be it known that I, LOUIS R. ALBERGER, a citizen of the United States, residing at New York, county of New York, and State of New York, have invented certain new and useful Improvements in Surface Condensers, fully described and represented in the following specification and the accompanying drawings, forming a part of the same.

10 This invention relates to surface condensers, its object being to provide a condenser of this kind in which the degree of the vacuum and the temperature of the water of condensation may be adjustable independently 15 of the amount of temperature of the cooling-water or other cooling medium passed through the condenser.

The usual method of condensation in that 20 class of engines with which surface condensers are employed is well known and need not be particularly described herein, it being understood that the exhaust-steam, being led by the exhaust-pipe of the engine to one end or side of the condenser, is condensed therein, 25 and the water of condensation, together with air and uncondensable vapor, is drawn off from the other end or side of the condenser by an air-pump, and is passed to the hot well, from which the boiler is fed.

30 The form of surface condenser in general use consists of a series of pipes connected at their ends by steam-tight heads, the whole being inclosed in a casing. The steam may be passed through the pipes and cold water 35 forced through the casing, or vice versa, as desired. This form of condenser is modified in many ways, the principle, however, remaining the same, by which a supply of cold water passed through the condenser cools the surface with which the exhaust-steam from the 40 engine is brought in contact and condensed.

While my improved condenser is of general application to condensing-engines of the class described, it is of especial value as applied to pumping-engines of this same class and will be described as applied thereto.

In condensing-engines in which, as described, the water of condensation is pumped to a hot well to supply the boiler, it is necessary that the condensation should be so adjusted that the temperature of the water de-

livered to the hot well by the air-pump should be as high as possible consistently with the production of the best vacuum. It is necessary, therefore, that every condensing-engine 55 of this class shall be provided with means by which the condensation and the temperature of the water drawn off from the condenser may be adjusted, and this adjustment has heretofore been secured by varying the 60 amount of water passing through the condenser.

In pumping-engines it is impracticable to vary the amount of water passing through the main in accordance with the requirement 65 of the condenser, and systems in which the condenser forms a part of the main and receives all the water passing through the latter and in which the water of condensation passes to the boiler without reheating have 70 failed to give the best results, especially as the relation of the water pumped to the steam expended varies greatly in this class of engines depending upon the pressure in the force-main and the amount and temperature 75 of the water pumped. It has heretofore been customary, therefore, to provide pumping-engines with either an independent water-circulating system for the condenser by which the amount of water passing through the latter 80 may be adjusted independently of the amount of water passing through the main, or with means for reheating the water of condensation. This necessitates either another and independent pump or a system of valves 85 and pipes to deflect a portion of the main water through the condenser. I secure a perfect adjustment of the condensation while permitting all the water of the main to pass through the condenser and avoid the use of 90 any independent circulating system or re-heater by providing a condenser in which the effectiveness of the total condensing-surface is adjusted by varying the proportions of the cooling medium acting upon different parts 95 of the condensing-surface.

For a full understanding of my invention a description of a condenser embodying my invention will now be given, reference being had to the accompanying drawings, forming a 100 part of this specification, in which like letters of reference indicate like parts, and in which—

Figure 1 is a longitudinal section of a condenser provided with a disk-valve for directing the flow of water within the condenser. Fig. 2 is a cross-section on the line 2 2 of Fig. 1. Fig. 3 is a longitudinal section of a condenser having a gate-valve, and Fig. 4 is a cross-section on the line 4 4 of Fig. 3.

Referring now particularly to Figs. 1 and 2, the condenser is formed of a casing A, provided with steam-tight heads B C, between which extend a series of pipes or tubes D, and a larger pipe or tube E, which pipes form the condensing-surface of the condenser. The casing A is provided with a port F, through which the exhaust-steam enters the condenser, and with a port G on the opposite side of the condenser, through which the water of condensation and the air are drawn from the condenser by the air-pump and led to the hot well.

The casing of the condenser is provided at each end outside the heads B C with chambers H I, communicating with the pipes of the condenser, and with which the water-main K connects for the passage of the water to and from the condenser, this main K being either the suction or force main of the engine, as preferred. The larger pipe E is preferably placed, as shown, centrally of the condenser and virtually forms a continuation of the main K through the latter between the chambers H I.

To control the flow of water through the pipe E, and consequently that through the pipes D, a valve *a* is provided, carried by a screw-rod *b*, provided with a handle *c*, by which it may be operated to carry the valve *a* to or from the main port. This valve may be placed either at the induction or discharge end of the condenser. By the closing movement of this valve the flow through the pipe E is retarded by the decrease in the area of the passage and increase in friction upon the valve and more of the water directed through the water-pipes D, and by the opening movement the effect is reversed.

In Figs. 3 and 4 a similar construction is shown, except that a gate-valve is used in place of the disk-valve *a*. This valve *d* is pivoted in lugs *e*, mounted on the head B and swings inside the pipe E, the valve being oscillated by means of the spool *f*, engaging the stem of the valve and moving on a screw-rod *g*, mounted in the casing of chamber H, and provided with a handle *i*.

It will be seen that in this construction the pipe E forms a part of the condensing-surface, and by the movement of the valve *a* or *d* the relative amounts of water acting upon the different parts of the condensing-surface may be adjusted as desired. By adjusting the valve to allow more water to pass through the pipe E, and consequently diminishing the amount of water passing through the pipes D, the temperature of the condensing-surface of the latter will be raised. By shutting off part of the water from the pipe E the amount

of water passing through the pipes D is increased and the temperature of the condensing-surface of the latter correspondingly lowered. While the amount of water passing through pipe E is increased or diminished exactly in inverse ratio to that passing through the pipes D, the effect of the water upon the condensing-surface of pipe E and pipes D is not the same on account of the larger bore of pipe E and the rise or fall in the temperature of the surface of pipes D only partially compensated for by the consequent fall or rise in temperature in the surface of pipe E. The temperature of the water of condensation and the degree of vacuum therefore will be varied by the movement of the valve, and an accurate adjustment of the condensation may thus be secured without varying the amount of water passing through the condenser, so that the vacuum produced and the temperature of the water of condensation shall bear to each other that relation which results in the greatest economy in the operation of the engine. The result stated will be obtained, although the condensing-surface of pipe E is exactly equal to the total condensing-surface of pipes D, since, as stated above, the cooling effect of the water in the pipes E and D does not vary as the amount. A wider variation for each movement of the valve may be obtained, however, by constructing the condensing-surfaces of different areas, so that the effect of the water is varied not only by the relative bores of the pipes E and D, but by the relative areas of the condensing-surface acted upon by the water as it is directed through the different parts of the condenser. By employing only two pipes of different bores or having condensing-surfaces of different areas a similar adjustment may be obtained; but the series give a wide variation, and this construction is preferable.

While I have shown a condenser formed of a series of pipes surrounded by a casing, my invention may be embodied in any other form of surface condenser, that shown being but one of the ordinary forms and selected as that found most convenient for use and best illustrating my invention. It is evident, also, that the special construction of the condenser shown and the means of adjustment may be varied widely by one skilled in the art without departing from my invention, and that any other suitable means may be employed for adjusting the relative amounts of water acting upon the different parts of the condensing-surface.

What I claim is—

1. A surface condenser provided with means for varying relatively to each other the amounts of cooling medium acting upon different parts of the condensing-surface, substantially as described.
2. The combination, with a surface condenser provided with two or more condensing-surfaces of different areas, of means for vary-

ing relatively to each other the amounts of cooling medium acting upon the different surfaces, substantially as described.

5. The combination, with a surface condenser provided with two or more condensing-pipes of different bores through which the cooling medium passes, of means for varying the amount of cooling medium passing through the different pipes, substantially as described.

4. The combination, with a surface condenser provided with two or more condensing-pipes of different bores and different condensing areas through which the cooling medium passes, of means for varying the amount of cooling medium passing through the different pipes, substantially as described.

5. The combination, with a surface condenser provided with a pipe through which a part of the cooling medium passes and which forms a part of the condensing-surface, of a valve controlling said pipe, whereby the relative amounts of cooling medium passing through said pipe and other parts of the condenser may be adjusted, substantially as described.

6. The combination, with a surface condenser provided with a series of condenser-pipes, and a pipe of larger bore through which a part of the cooling medium passes and which forms a part of the condensing-surface, of a valve controlling said larger pipe, whereby the relative amounts of cooling medium passing through the larger and

smaller pipes may be adjusted, substantially as described.

7. The combination, with the main of a pumping-engine, of a surface condenser through which the water of the main passes, the steam-exhaust entering said condenser, a discharge-pipe for the water of condensation, and means for adjusting relatively to each other the amounts of water acting upon different parts of the condensing-surface, substantially as described.

8. The combination, with the main of a pumping-engine, of a surface condenser provided with condensing-pipes of different bores through which the water of the main passes, the steam-exhaust entering said condenser, a discharge-pipe for the water of condensation, and means for varying the amount of water passing through the different pipes, substantially as described.

9. The combination, with the main K, of the casing A, pipe E, and series of pipes D, through which the water of the main passes, steam exhaust and discharge pipes F G, and a valve controlling the pipe E, substantially as described.

In testimony whereof I have hereunto set my hand in the presence of two subscribing witnesses.
